UNITED STATES PATENT OFFICE.

EDWARD McCUALEY, OF MINNEAPOLIS, MINNESOTA, ASSIGNOR OF ONE-HALF TO WILLIAM T. McCUALEY, OF OSGOODE, CANADA.

FLAX-PULLING MACHINE.

No. 891,362.

Specification of Letters Patent.

Patented June 23, 1908.

Application filed December 17, 1907. Serial No. 406,913.

To all whom it may concern:

Be it known that I, EDWARD McCUALEY, citizen of the United States, residing at city of Minneapolis, Minnesota, have invented 5 certain new and useful Improvements in Flax-Pulling Machines, of which the following is a specification.

My invention relates to improvements in flax pulling apparatus and is designed more 10 especially as an attachment which may be applied to the ordinary reaper or binder.

Among the objects of the invention are the following: First, to provide an apparatus which may be constructed at a low cost and 15 easily and quickly applied to an ordinary binder; second, to provide a simple and efficient construction which will simultaneously pull the flax over a space equal to the entire length of the ordinary cutter bar of an ordinary reaper, or mower, and finally, to provide 20 a construction in which a plurality of grasping members or fingers are used, each of which grips only a small portion of the flax whereby excessive bending or tearing of the 25 flax is avoided.

With these and possibly other objects in view, the invention includes the various features of construction, and arrangement and combination of parts hereinafter described and particularly set forth in the appended claims.

An embodiment of the invention is illustrated in the accompanying drawings in which:

35 Figure 1 is a plan view showing conventionally a sufficient portion of a reaper to illustrate the application of the invention thereto. Fig. 2 is a transverse section on an enlarged scale on line 2—2 of Fig. 1. Fig. 3 is a plan view showing two of the grasping arms, on a large scale, with the adjacent parts. Fig. 4 is a transverse section on line 4—4 of Fig. 3. Fig. 5 is a section on line 5—5 of Fig. 3. Fig. 6 is a sectional view of 45 one of the cams.

Referring by reference characters to these drawings the numeral 1 designates the framework of any suitable apparatus such as the reaper or binder which is mounted upon 50 wheels 2 and 3, the latter being provided with suitable projections 3^a upon its surface to enable it to act as a driving wheel to drive the various parts in the manner well understood by those skilled in the art.

The numeral 4 designates the grain platform but as this and the binder mechanism form no part of the present invention, the grain platform is only conventionally shown and the binder mechanism omitted for clearness of illustration.

60 In applying my attachment to a binder the sickle and fingers or guards would be omitted. At each end of the finger or guard bar and bolted thereto and to frame parts in rear thereof, are located cam plates or bars 5 and 6 which have cam tracks or faces as indicated at 7 and journal or bearing sockets 8 which receive front and rear shafts 9 and 10. These shafts carry sprocket wheels 11 and 12 over which pass sprocket chains 13, certain links 70 of which in turn carry a plurality of longitudinal hollow rods 14 of which six are found to be a convenient number. To each of these rods is rigidly secured a series of fingers 15, each finger being conveniently held in place 75 by having a split socket portion clamped around the tubular bar by the bolts 16. Each of these fingers 15 is provided with a lug or projection 17 which carries a pivot pin 18 on which is pivotally mounted the forked 80 portion 19 of an oscillating gripping finger 20. The arms of the forked portion extend down on opposite sides of the hollow rod or bar 14 and are slotted to engage the ends of a bolt or pin 21 which passes through elongated slots 22 in the hollow rod or bar 14 and through a hole in an inner reciprocating rod 22^a. It will thus be seen that as the rod 22^a is reciprocated the oscillating finger 20 will be swung first to one side into the open position which is shown in dotted lines in Fig. 3 90 and then in an opposite direction into the position shown in full lines, in which position, owing to the relative shape of the oscillating and stationary fingers, which is indicated in 95 cross section in Fig. 5, the flax will be securely gripped between the parts. The surfaces 7 of the cams 5 and 6 act upon rollers 23 and 24 secured at opposite ends of the inner rods 22^a and these cam surfaces are so shaped 100 that the fingers are closed on the flax when about 8 inches from the ground and maintained in their closed position while the flax is pulled and carried by the endless chains of the binder. In this position the action of the 105 cams causes the oscillating fingers to be open allowing the flax to be dropped upon the can-

2
vas or deck in a position parallel therewith and perpendicular to the line of travel of the machine.

The endless chain carriers are rotated by 5 power applied conveniently to the extended end of the shaft 9 by a gear wheel 25 keyed on the end thereof which meshes with another gear or pinion 26 on the countershaft 27 which in turn is operated by a sprocket 10 chain and pinion connection 28 with the main driving wheel 3. A suitable clutch 29 may be provided for throwing the pulling mechanism into and out of operation.

As there is naturally more or less looseness 15 in all chains with the hollow rods 14 held and guided solely by the links there would be more or less objectionable rocking or vibrating of the links rods and fingers. To avoid this I secure on opposite ends of each rod 14 20 an arm 14^a extending at an angle to the fingers and having its end adapted to be guided by a cam groove 14^b on the corresponding end plate.

While I have described my invention as an 25 attachment to an ordinary reaper or binder it will be understood that it is not limited in this respect but may be embodied in any suitable machine capable of properly supporting and operating the gripping and pulling mechanism hereinbefore described.

Having thus described my invention what I claim is:

1. In an apparatus of the character described, the combination with a suitable supporting frame, of a pair of endless carriers supported thereby, a plurality of rows of gripping devices carried by said endless carriers, and means for opening and closing all the gripping devices of each row at determined points in their travel, substantially as described.

2. In combination, a suitable wheeled supporting frame, a pair of endless carriers thereon with means for operating them, a 45 plurality of rows of gripping devices supported by said carriers, cams carried by the frame in proximity to the endless carriers and means coacting with said cams for operating the gripping devices upon the movement of the carriers, substantially as described.

3. In combination, a suitable frame, a plurality of endless carriers supported thereby,

a plurality of bars carried by and extending between said endless carriers, a series of 55 gripping devices carried by each bar and including movable members, a reciprocating element mounted in proximity to each bar and operatively connected with the movable elements of the gripping devices, and stationary cams supported from the frame for operating said reciprocating elements, substantially as described.

4. In combination, a suitable frame, endless carriers supported thereby, a plurality of 65 hollow bars operatively connected with said endless carriers, a plurality of stationary fingers carried by each bar, a movable gripping finger pivotally mounted in proximity to each stationary finger, a rod mounted to reciprocate within each hollow bar and projecting at the ends beyond the same and stationary cam devices supported from the frame and coacting with said projecting ends. 70

5. In combination, a suitable frame, endless carriers supported thereby, a plurality of hollow bars carried by said carriers, stationary fingers secured to said bars, a plurality of movable fingers pivotally mounted between the stationary fingers having portions 80 overlapping the hollow bars, a reciprocating rod mounted within each hollow bar, said hollow bars having elongated slots and pins or projections carried by said rods, and extending through said slots into operative engagement with the overlapping portions of the movable fingers and means for reciprocating said rods during the movement of the said carriers, substantially as described. 85

6. In combination with a suitable frame 90 having a grain platform, a plurality of endless carriers supported in advance of said platform and extending in the direction of the line of travel of said platform, a plurality of rows of gripping devices carried by said carriers and arranged parallel with the forward edge of the deck, and means for causing all the grippers of each row to be closed when they are remote from the deck and opened when they are in proximity thereto. 95

In testimony whereof, I affix my signature in presence of two witnesses.

EDWARD McCUALEY.
